UNITED STATES PATENT OFFICE

151,615

DESIGN FOR A PHOTOGRAPHIC COLOR- TRANSPARENCY ANALYSIS MACHINE

Iredell Eachus, Wayne, Pa., and Norman
Macbeth, Jr., New York, N. Y.

Application February 26, 1948, Serial No. 144,754

Term of patent 7 years

(Cl. D61—1)

To all whom it may concern:

Be it known that we, Iredell Eachus and Norman Macbeth, Jr., citizens of the United States, residing at Wayne, Delaware County, Pennsylvania, and New York, county of New York, State of New York, respectively, have invented a new, original, and ornamental Design for a Photographic Color-Transparency Analysis Machine, of which the following is a specification, reference being made to the accompanying drawing, forming a part thereof, in which:

Fig. 1 is a front elevational view of a photographic color-transparency analysis machine, showing our new design;

Fig. 2 is a side elevational view thereof;

Fig. 3 is a rear elevational view thereof; and

Fig. 4 is a perspective view from the rear thereof.

We claim:

The ornamental design for a photographic color-transparency analysis machine, substantially as shown.

IREDELL EACHUS.

NORMAN MACBETH, JR.
